UNITED STATES PATENT OFFICE.

LUTHER THOMAS AND FENWICK GEORGE HATT, OF SAN ANTONIO, TEXAS.

GRAVE-FILLING APPARATUS.

Application filed December 30, 1922, Serial No. 610,047. Renewed November 24, 1925.

The object of our said invention is the provision of an apparatus, designed to receive the dirt from a grave, and adapted subsequently to the placing of a casket in the grave to facilitate the filling of the grave.

To the attainment of the foregoing, the invention consists in the improvement as hereinafter described and definitely claimed.

In the accompanying drawings, forming part of this specification:

Figure 1 is a front elevation of our novel apparatus, the track rails being shown in transverse section.

Figure 2 is an end elevation of the same.

Figure 3 is a longitudinal vertical section taken in the plane indicated by the line 3—3 of Figure 2.

Figure 4 is a transverse vertical section taken in the plane indicated by the line 4—4 of Figure 1.

Figure 5 is a detail perspective showing the members comprised in each of the couplings for connecting the sections of the body of the apparatus.

Similar numerals of reference designate corresponding parts in all of the views of the drawings.

Our invention contemplates the arrangement of track rails 1 or timbers 2, and the disposition of the said rails 1 and timbers 2 at or adjacent to the opposite ends of a grave site.

Our invention also contemplates the mounting on the said rails 1 of a frame which includes a hopper bottom 3 and arms 4 that extend outwardly from the corners of the hopper bottom 3 and are provided at their undersides and adjacent to their outer ends with casters 5, the wheels 6 of the casters being circumferentially grooved so as to preclude the possibility of the apparatus being accidentally derailed. The hopper bottom 3 has guides 7 adjacent to the ends of its mouth to receive a valve plate 8.

It is understood that the casters (part 5) works pivotally under the base of (part 4) with ball bearings between allowing the caster to turn in any direction on the ball bearings; this is made necessary so that they will manipulate freely from any position. For instance, the caster must necessarily be completed with a swivel swing, so that the approach of the grave could be had from the foot or head of grave, where shrubbery or other obstructions would make the other po-

sitions prohibitive. (Also oil holes to facilitate oiling of all bearings.)

The hopper bottom 3 is provided at its upper edges with rests for the end walls 9 and the back wall 10 and front wall 11 comprised in the body of the apparatus, the back and front rests being equipped by preference with longitudinal edge strips 12 within which the back wall and front wall are designed to be arranged as illustrated. In the present and preferred embodiment of our invention the front wall 11 is made up of a lower section 11^a and an upper section 11^b, the lower section being provided with an outer retaining strip 11^c which projects above its upper edge as illustrated so as to confine the lower edge of the upper section 11^b when said section is superimposed edgewise on the section 11^a. The end walls, the back wall and the described sections of the front wall are preferably provided with handles 13 of appropriate character to render convenient the handling of the said walls and wall sections. We also prefer to provide the end walls 9 with appropriate appurtenances such as 15 for the connection of cables (not shown) through which the apparatus can be conveniently moved on the track rails 1.

In the preferred embodiment of our invention the back, end and front walls are removably arranged on the described rests of the hopper bottom 3, and are designed to be disassociated from the said hopper bottom 3 and disconnected from each other for convenience in storage as well as in handling the apparatus. Therefore, we detachably connect the end walls to the back wall, and we also detachably connect the sections of the front wall to the end walls. Each of the couplings for effecting the said detachable connections is made up of a member 16 fixed at 17 to the inner side of one wall and having an angularly disposed arm 18 notched as indicated by 19, said notch being in the upper end of the arm and adjacent to the body plate 20 of the member, and a second member 21 pivotally connected by preference to the inner side of a wall or wall section at right angles to the first-named wall and having a body plate 22 and an angularly disposed arm 23 with a notch 24 in the lower end of the said arm 23. The said members are engaged and their walls are connected by moving the members 21 into engagement with the members 16, as

2
illustrated in Figures 3 and 4, and from this it follows that to disconnect the members of the couplings it is simply necessary to move one wall or wall section upwardly relative 5 to the wall or walls at right angles thereto. It will also be appreciated that when the coupling members 16 and 21 are properly engaged there is absolutely no liability of the walls or wall sections becoming casually 10 disconnected.

At 25 is a cover designed to be placed over the body of the apparatus and having pendant marginal flanges. The said cover 25 may be and preferably is used under all conditions 15 with a view hiding the dirt and improving the appearance of the apparatus when the body is filled with dirt. The said cover 25 is particularly advantageous, however, for use when the grave excavation is 20 made one or more days prior to a burial and rain falls in the meantime. In the latter event it will be understood that the cover 25 will prevent the rain from soaking the dirt in the apparatus, and when the apparatus 25 is moved to a position above the excavation the apparatus will prevent rain from entering the excavation. The said cover 25 is also provided by preference with appropriate handles 27.

30 The body walls and wall sections are superimposed on the rests at the edges of the hopper bottom 3 and are connected together in the manner before described, and therefore it is deemed unnecessary to describe in detail the manner in which the walls and wall sections are placed on the hopper bottom 3 and are connected together, and the manner in which the walls and wall 35 sections are disconnected and removed from 40 the hopper bottom 3.

In the practical use of our novel apparatus, the track rails are arranged at or adjacent to the ends of a grave site and the apparatus is moved to a position alongside 45 the grave site so that as a grave is dug the dirt removed from the grave can be readily deposited in the body of the apparatus, it being understood that the valve plate 8 is at this time in closed position. At the commencement 50 of the operation, the lower front section 11^a alone is in place, and when the body of the apparatus is filled up to the upper edge of the said section 11^a, the upper section 11^b is superimposed on the section 55 11^a and is fastened in position. The operation is then continued until all of the dirt necessary is removed from the grave and deposited in the body of the apparatus. Under ordinary conditions after the completion 60 of the operation described the apparatus is moved on the rails 1 to a point some little distance from the grave, so that the apparatus will not interfere in any measure with a burial ceremony.

65 Subsequently to the placing of a casket

in the grave, the apparatus is moved on the rails 1 until the hopper bottom is above and coincident with the grave. With this done the valve plate 8 is withdrawn or moved to open position when the dirt contained in the body of the apparatus will fall in the grave. For convenience in manipulating the valve plate 8 we provide the levers 30 on the back wall 10, and links 31 interposed between and pivotally connected to the lower arms of the 75 said levers 30 and the valve plate 8.

It will be apparent that after the grave is filled with dirt in the manner described, the apparatus can be expeditiously and easily moved on the rails 1 from the position above the grave so as not to interfere with the tamping of the dirt in the grave.

It is within the purview of our invention to make our novel apparatus of any material or materials compatible with the purpose 85 of the apparatus, though we prefer for the sake of durability to make the back wall, end walls and front wall sections of boiler plate of appropriate thickness or any other suitable sheet metal. We would also have it 90 understood that the hopper bottom can be formed of sheet metal while the arms 4 can be made of metal or wood in the discretion of the manufacturer of the apparatus.

By preference the end walls 9 are detachably connected with the hopper bottom 3, keepers 14 on the end walls being employed in combination with pivoted latches 14^x on the hopper bottom for the purpose, and the said latches 14^x being adapted to be swung 100 into and out of bifurcations 15^x in the keepers. On the latches 14^x are apertured heads, as shown.

We have entered into a detailed description of the construction and relative arrangement of the parts embraced in the present and preferred embodiment of our invention in order to impart a full, clear and exact understanding of the said embodiment. We do not desire, however, to be 110 understood as confining ourselves to the specific construction and relative arrangement of parts inasmuch as in the future practice of the invention various changes and modifications may be made such as fall 115 within the purview of our invention as defined in our appended claims.

Having described our invention, what we claim and desire to secure by Letters-Patent, is:—

1. The combination of a hopper bottom with rests at its upper edges and flanges on the back and front rests, a back wall superimposed on the back rest within the flange thereof, end walls superimposed on the end rests, a lower front wall section superimposed on the front rest within the flange thereof and having a flange at its upper edge, an upper front wall section superimposed on the lower front wall section and 130

arranged within the flange thereof, and means detachably connecting the end walls to the back wall, and means detachably connecting the front wall sections to the end walls.

2. The combination of a hopper bottom with rests at its upper edges and flanges on the back and front rests, a back wall superimposed on the back rest within the flange thereof, end walls superimposed on the end rests, a lower front wall section superimposed on the front rest within the flange thereof and having a flange at its upper edge, an upper front wall section superimposed on the lower front wall section and arranged within the flange thereof, and means detachably connecting the end walls

to the back wall, and means detachably connecting the front wall sections to the end walls, each of the said means comprising a 20 member fixed to the inner side of one wall or section and having an angularly disposed arm with a notch in the upper end thereof, and a member connected to a wall or section at right angles to the first-named wall or section and having an angularly disposed arm with a notch in its lower end and adapted to interlock with the first-named angularly disposed arm.

In testimony whereof we affix our signatures. 30

LUTHER THOMAS.
FENWICK GEORGE HATT.
